[57] CLAIM

The ornamental design for a purse, as shown and described.

DESCRIPTION

FIG. 1 is a front perspective view of a purse showing my new design; the broken line showing a shoulder strap is for illustrating environmental elements only;

FIG. 2 is a front elevational view thereof;

FIG. 3 is a left end elevational view thereof;

FIG. 4 is a right end elevational view thereof;

FIG. 5 is a rear elevational view thereof;

FIG. 6 is a top view thereof;

FIG. 7 is a bottom view thereof; and,

FIG. 8 is a front perspective view thereof, with the purse in the open position.

The broken lines shown on the purse represent conventional stitching.
